UNITED STATES PATENT OFFICE.

NORBERT ROSENBAUM, OF NEW YORK, N. Y.

DESIGN FOR A SLIPPER.

Application filed August 29, 1925. Serial No. 14,638. Term of patent 3½ years.

To all whom it may concern:

Be it known that I, NORBERT ROSENBAUM, a citizen of the United States of America, residing at 616 West 113th Street, in the borough of Manhattan, city, county, and State of New York, have invented a new, original, and ornamental Design for a Slipper, of which the following is a specification, reference being had to the accompanying drawing, forming part thereof.

In the drawings Figure 1 is a side elevation of the left hand side looking toward the

toe of a slipper embodying my design. Figure 2 is a top plan view of Figure 1 and Figure 3 is a side elevation of the right hand side looking toward the toe of a slipper embodying my design.

I claim:

The ornamental design for a slipper as shown.

Signed at New York city, county of New York, State of New York, this 28th day of August, 1925.

NORBERT ROSENBAUM.
